TROUSER BLOUSING METHOD

Andrew A. Aines, United States Army,
Petersburg, Va.

Application September 24, 1948, Serial No. 51,004

2 Claims. (Cl. 2—314)

(Granted under the act of March 3, 1883, as
amended April 30, 1928; 370 U. S. G. 757)

1

The invention described herein, if patented, may be manufactured and used by or for the Government for governmental purposes without the payment to me of any royalty thereon.

This invention relates to a novel method for blousing or bulging the bottoms of trouser legs, as practiced, for example, by parachute troops.

As now practiced the lower edges of the trouser legs are stuffed into the tops of the wearer's boots or relatively high shoes. Such procedure not only tends to impair the normal circulation of blood in the wearer's legs, but also produces an irregular and unsightly appearance among troops, due to the fact that the trouser bottoms will be stuffed into the shoes varying degrees according to the whim of the wearer as well as according to the amount of space available between the boot top and leg of the wearer.

It is an object of the present invention therefore to provide a method for blousing trouser leg bottoms which avoids the necessity of inserting them in the boot tops, thereby eliminating the defects just mentioned, namely, interference with the circulatory system of the wearer and the unsightly appearance of irregular or non-uniform blousing.

Another object of the invention resides in the provision of a rather simple and inexpensive tying means comprising a strap for binding the trouser bottoms about the wearer's legs at a point just above the boot tops and detachably anchoring the straps to the boot tops.

Other objects and advantages of the invention will be apparent from the following description when taken in connection with the accompanying drawings in which,

Figure 1 is a perspective view of the lower portion of the leg of the wearer showing the novel attachment about to be applied to the boot;

Figure 2 is a similar view showing a further step in the procedure of installing the blousing attachment;

Figure 3 is a plan view of the device, partly broken away;

Figure 4 is a front elevational view showing the appearance of the trousers as bloused with the new attachment;

Figures 5 and 6 are perspective views of modified means for attaching the device to the boot top; and

Figures 7 and 8 are a side elevational view, partly in section, and a vertical sectional view respectively, of still further variations of the means for attaching the device to the boot.

Paratroopers and others for which the present

2

device is intended, wear boots or shoes provided with a relatively high upper and such shoes are indicated in Figures 1 and 2 by the numeral 1. In the form of the invention shown in Figures 1 to 3 inclusive, these shoes are provided with backstays 2 and at a point adjacent the upper end of the stays one portion 3 of a conventional type of snap fastener is riveted or otherwise secured.

The means for attaching the bottom of the trouser to the legs of the wearer at a point slightly above the top of the boots comprises an elongated strap 4, provided with a conventional buckle 5 at one end and apertures 6 at the other end for cooperation with the buckle. Adjacent the buckle portion of the strap, a depending strap 7 is secured as indicated by the numeral 8. This depending strap 7 is provided with a complementary snap fastener 9 for cooperation with the fastener 3 mounted adjacent the top of the backstay 2.

In applying this device, as clearly indicated in Figures 1 and 2, the snap fastener 9 is first applied to its counterpart 3 on the boot and the leg of the trouser is then positioned so as to slightly overlap the top of the boot, and the material of the trouser leg is then folded or gathered in a manner which will be readily understood, so as to snugly fit about the wearer's leg. The strap is then drawn tight about the trouser leg just above the boot top, as clearly indicated in Figure 2, and the buckle fastened. Thereafter, the excess portion of the material of the trouser legs is folded downwardly over the strap 4 and the boot top so as to blouse the same in the manner indicated in Figure 4.

In the modified construction shown in Figure 5, the depending strap is indicated by the numeral 10 and in lieu of the conventional snap fastener shown in Figures 1 to 3, the strap 10 is provided with an eye or loop 11 pivotally connected to the lower end of the strap and cooperates with a hook 12 secured adjacent the upper end of the boot top. In Figure 6, an equivalent strap 13 is provided with a necked-in loop portion 14 of the garter type pivoted to the lower end of the strap and adapted to cooperate with a pin or button 15 fixed to the backstay of the shoe adjacent the upper portion thereof.

The modified construction shown in Figure 7 for attaching the depending strap 16 to the shoe 50 is quite similar to that shown in Figure 5, but differs therefrom in that the loop or eye 17 has its lower portion shaped into the form of a wedge 18, so as to facilitate the engagement of the eye or loop over the hook portion 19 fixed to the shoe at a point slightly below its top. The modi-

fied construction shown in Figure 8 is very similar to that shown in Figures 1 to 3 inclusive, but in this latter instance the snap fastener, which is mounted directly on the backstay of the shoe in Figures 1 to 3 inclusive, is mounted on a flexible strip 20, which has its lower end fixed to the back of the shoe at a point spaced below the top thereof and its upper end fixed to the top of the shoe so as to provide a loop to which the snap member 21 is attached.

The device of the present invention as outlined above and as illustrated in the drawings is of inexpensive construction and is easily applied to the wearer's shoe, and just as easily attached to the trouser leg so as to permit blousing of the lower portion of the trousers. Moreover, the construction and arrangement is such as to permit uniformity in the blousing of the trousers and yet eliminates the objectional feature of stuffing the trouser legs in the top of the boots, which, as mentioned above, has the disadvantage of impairing, if not entirely cutting off the circulation of blood in that portion of the wearer's leg.

I claim:

1. The method of blousing trouser bottoms which comprises coupling a strap means to the wearer's shoe at a point slightly below the top thereof, raising the trouser bottom to a point adjacent the top of the shoe with the bottom of the trouser slightly overlapping the top of the shoe and the coupling point, applying the strap means about the trouser bottom to bind it to the

wearer's leg at a point just above the shoe top, thereby causing excess trouser material to fold down over the shoe top.

2. The method of blousing trouser bottoms which comprises coupling a strap means to the wearer's shoe at a point slightly below the top thereof, raising the trouser bottom to a point adjacent the top of the shoe with the bottom of the trouser slightly overlapping the top of the shoe and the coupling point, and applying the strap means about the trouser bottom to bind it to the wearer's leg adjacent the shoe top, thereby causing excess trouser material to fold down over the top of the shoe.
